UNITED STATES PATENT OFFICE.

HANS EBERHARDT, OF BERLIN, GERMANY.

SPRING-BUTTON FOR GLOVES, ARTICLES OF CLOTHING, SHOES, AND THE LIKE.

No. 921,524.

Specification of Letters Patent.

Patented May 11, 1909.

Application filed December 7, 1907. Serial No. 405,540.

To all whom it may concern:

Be it known that I, HANS EBERHARDT, resident of 1 Flensburgerstrasse, Berlin, Germany, manufacturer, have invented a new 5 and useful Improvement in Spring-Buttons for Gloves, Articles of Clothing, Shoes, and the Like.

My invention consists in manufacturing 10 spring-buttons which are made undetachable by a lateral pull, no matter on which side, by a peculiar simple arrangement. In consequence of this new feature the button can be used also for such objects in which a great lateral pull takes place, for instance 15 shoes and boots. The applicability of the button is, in consequence of the present arrangement, considerably enlarged.

The new feature consists in giving to one 20 part of the button, which *per se* is already known, with its border a point of support on the border of the other part in any pulling direction. The lateral pull exerted on the button finds therefore in the first place on this point of support a resistance and from 25 this the pulling force is transmitted under a very acute angle to the juncture properly speaking of the button. In consequence of the transmission of force under an acute angle the said juncture is influenced by the 30 pull only in a very small degree. Moreover with a lateral pull one part of the button must, as is well known, be turned out of the other. By the arrangement of a supporting point on the border of one of the parts of the 35 button it is made impossible, by the lengthening of the radius from the supporting point of the resilient or rigid part of the button toward the friction-surface of the latter, for the parts to become separated.

40 The arrangement of the point of support in question can be made in different ways. The most simple form is a projecting border on the upper or lower part of the button or a recess in the button-plate, so that the plate 45 of the other part can be inserted into the same. The object of my invention is shown in this form of construction on an enlarged scale on the accompanying drawing, in which—

50 Figure 1 is a cross-section, Fig. 2 shows the working parts of this button, Fig. 3 is a modified form of the button shown in Fig. 2.

The button according to Fig. 1 consists in

the usual manner of an upper, female part *a*, 55 into which is forced the resilient or rigid part *b*. With the female part *a* is connected the hood *c* with the guide-rings *d* and *e*. Between the ring *e* and the flat border of the female part *a* is the stuff, on which this part of the button is fixed, compressed by forming 60 a border around the border of the neck of the part *a*. The other part of the button consists of the resilient or stiff crown *b* and the plate *g* for compressing the stuff *h*. The new feature consists therein that the flange *i* 65 of the part *b* of the crown is sunk into the flange *k* of the female part, so that the edge of the flange *i* finds a support on the flange *k*. This arrangement may, of course, also be the reverse, so that (Fig. 3) the border of 70 the female part *a'* is sunk into the border of the part *b'* of the crown.

The mode of working of the new construction can be seen from Fig. 2. If the pull takes place with both buttons in the direction of the arrows 1 the arcs 2 indicate the ways which the crowns move with regard to the female parts. It will be seen that the path of the crown of the new button according to Fig. 2 passes through the female part, 75 whereas with the old button hitherto used the crown requires only a small pressure in order to pass along the inner wall of the female part. The greater resistance of the new button against a lateral pull is therefore 80 quite evident.

Having now described my invention what I claim is:

1. In spring buttons, the combination of a crown part, a female part, both of which 90 are provided with flanges, and means on the flange of one part for supporting the border of the flange of the other part, as and for the purpose specified.

2. In spring buttons, the combination of 95 a crown part, a female part, both of which are provided with flanges and the flange on one part being provided with a recess for supporting the border of the flange of the other part.

In witness whereof I have hereunto set my hand in presence of two witnesses.

HANS EBERHARDT.
